UNITED STATES PATENT OFFICE.

WALTER TRIPP AND HENRY ALBERT TRIPP, OF EAST WILLIAMSON, NEW YORK.

APPLE PARING AND CORING MACHINE.

SPECIFICATION forming part of Letters Patent No. 363,022, dated May 17, 1887.

Application filed August 28, 1886. Serial No. 212,100. (Model.)

To all whom it may concern:

Be it known that we, WALTER TRIPP and HENRY ALBERT TRIPP, citizens of the United States, residing at East Williamson, in the 5 county of Wayne and State of New York, have invented a new and useful Improvement in Apple Paring and Coring Machines, of which the following is a specification.

Our invention relates to improvements in 10 apple paring and coring machines; and it consists of the peculiar combination and novel construction and arrangement of the various parts for service, substantially as hereinafter fully described, and particularly pointed out 15 in the claims.

The object of our invention is to provide an improved machine for automatically paring, coring, and expelling the apples which shall possess superior advantages over others that 20 have preceded it in points of simplicity, strength, and durability of construction, efficiency of operation, and cheapness of manufacture.

A further object of our invention is to provide 25 an improved machine of the class named which shall completely separate and discharge from the machine the parings, cores, and the pared fruit, so that the fruit and parings are not discharged in a common vessel, and thus 30 dispense with the labor of separating them.

In the accompanying drawings, which illustrate 35 an apple paring and coring machine embodying our invention, Figure 1 is a top plan view. Fig. 2 is a side elevation of the machine with the parts in position for beginning the operation of paring the fruit. Fig. 3 is a vertical longitudinal sectional view on the line $x x$ of Fig. 1. Fig. 4 is a side elevation of the machine corresponding to Fig. 1, 40 showing the parts in the position which they assume after the operation of paring has been completed. Fig. 5 is a transverse sectional view on the line $y y$ of Fig. 2, looking in the direction indicated by the arrow 1. Fig. 6 is 45 a detached perspective view of the rotary disk carrying the cutter-arm. Fig. 7 is a detail view of the doffer, together with the flanged collar and the doffer-arm for actuating the same. Fig. 8 is an enlarged sectional view of

the fixed cam and the swinging knife-arm, 50 together with the rotary cam-disk and the doffer-arm, to more clearly show the details in the construction thereof. Fig. 9 is a sectional view on the line $z z$ of Fig. 2.

Referring to the drawings, in which like 55 letters of reference denote corresponding parts in all the figures, A designates the frame of the machine, which is rigidly affixed or secured to a table or other suitable support. This frame is provided at its lower portion with a 60 horizontal base, B, which is cast or formed in a single piece of metal, and has an inclined or beveled flange or rib, b, arranged longitudinally thereof. This inclined flange or rib b of the horizontal base terminates at a point be- 55 yond the outer extremity of the rotary fork, which will be hereinafter described, and the base is further provided at the extremity of the inclined rib or flange with a discharge-plate, B', which is inclined in reversed direction 70 to the rib or flange b, one side of the said inclined discharge-plate being provided with a raised rib or flange, b', to prevent the fruit falling thereon from passing over the same side of the machine as the parings, and the 75 lower side of the said plate being left open and free to permit the fruit to pass off the same without hinderance. This inclined discharge-plate B' is located immediately in front of a fixed stop for throwing or drawing the pared 80 fruit off the coring-tube during the retrograde movement of the latter, so that the pared fruit will fall upon the said plate and be deflected or discharged to one side of the machine.

From the foregoing it will be seen that by 85 means of the oppositely-inclined discharge flange and plate b B', respectively, the parings from the fruit and the pared fruit itself are discharged from the machine on opposite sides thereof, and thereby effecting a saving in time 90 and labor, as the fruit and parings are separated by the machine, and do not, therefore, require to be separated by hand after they leave the machine. The base B of the main frame A is further provided with a horizontal 95 arm or extension, C, which is elevated above the plane of the base and arranged to one side of the same, so as to be out of line therewith.

This horizontal arm or extension is provided with a transversely-curved groove, *c*, in its upper side, and to one of the sides of the arm is rigidly affixed a way or guide-rod, *C*, which 5 is preferably circular in cross-section and immovably held in place, the sliding frame, hereinafter described, being supported at one end upon the extension or arm and guided in its reciprocating movements by the guide-rod *C*, 10 all as presently described.

The main frame *A* of the machine is provided at one end with a vertical standard or upright, *D*, which is preferably curved longitudinally, so that its upper extremity will overhang the horizontal base *B*, the said base and standard of the frame being cast or formed integral with each other. This vertical standard *D* is provided with integral bearings *d d'*, which are arranged one above the other and 15 parallel with each other, and in these bearings are journaled shafts *E F*, which rotate or turn freely therein, and are arranged parallel with each other, as will be readily understood. The upper horizontal shaft, *E*, of the machine constitutes the driving-shaft, to which the power 20 is applied to operate all of the various devices or mechanisms for paring and coring the apples, and the latter shaft, *F*, carries the fork on which the fruit is placed and held to be operated upon by the knife.

The driving-shaft *E* of the machine carries a fly-wheel, *E'*, at its outer extremity, which is rigidly affixed thereto in any suitable manner, and to this fly-wheel is secured a crank-handle, *e*, to which the power is applied in order to rotate the same. The fly-wheel has gear or cog teeth on its periphery, with which 35 mesh the similar teeth on a small gear-pinion, *f*, that is rigidly secured to and rotates with the fork-carrying shaft *F*, whereby the two shafts *E F* are geared together for simultaneous operation, as is obvious.

The inner extremity of the driving-shaft *E* has a small beveled gear-pinion, *E''*, rigidly secured thereto, and this beveled pinion meshes with and drives a rotary cam-disk, *G*, which is arranged in a horizontal position above the plane of the driving-shaft. This cam-disk *G* has its under outer edges beveled or inclined 45 and provided with gear-teeth *g*, with which mesh the teeth of the bevel-pinion to rotate the said disk, and this disk has a vertical flange, *G'*, formed integral therewith, the periphery of this flange having a series of gear-teeth, *g''*, formed thereon for about one half its length, while the other half is left smooth and plane, for a purpose presently described.

The upper outer extremity of the vertical standard *D* of the carrying-frame has a vertical bearing, *D'*, formed therein, in which is journaled the vertical stem or shaft of the horizontal rotary cam-disk *G*, and the said extremity of the vertical standard has an enlarged cam-plate, *H*, formed integral therewith, the 60 lower under side of the cam-plate having a downwardly-projecting rib or shoulder, *h*,

thereon, and which has its sides inclined or curved so as to cause the inner upper end of a swinging arm, *I*, to be deflected downwardly, whereby the lower end of the said arm, which 70 carries the knives, will be elevated during a portion of the orbit described by the arm, as will be presently explained. This fixed cam-plate *H* has its inclined rib or flange located to one side of the vertical stem or shaft of the 75 rotary cam-disk, and the plate has guide-arms or fingers *h'* extended or projected from opposite sides thereof to prevent the reciprocating frame *O* from vertical movement or displacement.

The swinging arm *I* is provided at its upper end with trunnions or shafts *i*, which are journaled in bearings *i'* on the lower under side of the rotary disk *G*, so that the arm is carried by the disk during the rotary movements 85 thereof, and at the same time is free to swing on its pivots or trunnions independently of the motion of the disk, whereby the arm is free to bear against and accommodate itself to any uneven surfaces in the apple or other fruit 90 that is being operated upon in the machine. The upper end of the said swinging arm has an extension or finger, *i''*, which passes through a suitable slot or opening in the rotary disk, and this finger impinges against the inclined 95 sides of the rib or flange *h* on the fixed cam-plate *H*, as shown. The lower free end of the swinging arm is enlarged and provided with oppositely-inclined flanges *I'*, which are formed integral therewith and arranged parallel with each other at their contiguous edges, and these flanges are provided with transverse slots *k*, through which are passed the binding-screws *k'*, that serve to secure the cutter knives or blades *K* to the said flanges. These 100 blades or knives *K* bear against the inclined flanges of the swinging arm, and therefore assume the inclination of the flanges, the sharpened cutting-edges of the knives being arranged in close proximity to but out of contact 105 with each other, so that they are caused to properly act upon the fruit and only enter the same deep enough to pare off a thin piece of the skin, the depth to which the blades can enter the fruit being regulated by means of 110 set-screws working in the slots of the flanges, as is obvious. The swinging knife-carrying arm is provided at or near its middle with a laterally-extended lug, *l*, to which is connected one end of a coiled spring, *L*, and the 115 opposite end of this spring is secured to the lower under side of the rotary disk *G*, so that both the spring and the swinging arm are carried by the rotary disk in its movements.

The rotary disk is provided with an upwardly-extended rib or shoulder, *G''*, which has an inclined and beveled side and an abrupt side, and against this shoulder takes or bears the inner end of a finger, *m*, that is arranged at right angles to the doffer-arm *M*. This 125 doffer-arm is pivoted at or near its upper end on the vertical standard *D* of the main frame 130

A by means of a transverse pin or rivet, m' , and the lower end of this doffer-arm has an open ring or collar, m^2 , formed integral therewith. This open ring or collar is inclined or 5 bent at an angle to the arm M, and it fits and takes around the fork-carrying shaft F, so that the collar or ring can act upon a rib or flange, m^3 , that is formed around the periphery of a doffer-collar, M'. This doffer-collar is fitted to 10 slide very freely back and forth on the fork-carrying shaft F with the doffer-arm, and this arm is pivoted in such manner so as to swing back and forth parallel with the shaft F, while the shaft can rotate very freely without ob- 15 struction from the said arm.

The fork F' of the fork-carrying shaft F consists of a series of tines, which are separated from one another, so as to hold and engage the apple very securely, and on the shaft is fitted 20 a doffer-sleeve, N, that is free to move longitudinally on the shaft in front of the doffer-collar M', the said sleeve having a series of longitudinal slots, n, which correspond in number with the number of tines employed. The for- 25 ward end of the sleeve intermediate the slots therein normally fits between the tines of the fork, so that the sleeve is prevented from rotary movement on the shaft F, and when the end m of the swinging doffer-arm is acted upon 30 by the inclined portion of the rib or shoulder on the disk G the collar or open ring on the said arm impinges upon the doffer-collar M', which in turn bears against the rear solid end of the doffer-sleeve to force the latter forwardly and 35 cause the tines of the fork to ride in the slots of the longitudinally-movable sleeve.

O designates the sliding or reciprocating frame, which is actuated by the rotary disk G to move the coring-tube forward to pass 40 through the fruit and extract the core therefrom. This reciprocating frame comprises the parallel bars o, which are provided on their under sides with the gear-teeth, with which engage the teeth g^2 of the rotary disk G, the inclined bow-shaped connecting-piece o' , cast or 45 formed integral with the front ends of the side bars, o, and the segmental piece o^2 , connecting the rear ends of the parallel bars o, and having an arm, o^3 , extended rearwardly there- 50 from. The parallel bars o, having the gear-teeth, are arranged above the rotary disk G and beneath the lateral guide-arms of the fixed cam-plate H, so that the arms will prevent the frame from vertical play, and the teeth on the 55 depending flanges of the reciprocating frame engage with the teeth of the rotary disk alternately—that is to say, during one half of the rotation of the disk G the teeth thereof are engaged with the teeth of one of the bars o to 60 slide or move the reciprocating frame in one direction, and during the other half of the rotation of the disk the teeth thereof move or force the frame in the reverse direction.

P designates a hanger, which depends from 65 the extended arm o^3 of the reciprocating frame. This hanger is rigidly affixed in any suitable

manner to the extended arm of the reciprocating frame, so that it is moved simultaneously therewith, and the lower end of the hanger has a tubular guide, p, which encompasses the 70 circular guide of the arm or extension of the horizontal base, this tubular guide sliding freely over the guide rod and preventing any lateral play of the reciprocating frame at the rear end thereof.

R designates the coring-tube, which has a sharpened cutting-edge at its front end, so as to cause it to readily enter or penetrate the apples, and this coring-tube is arranged in line with the horizontal fork-carrying shaft F 80 of the machine, the diameter of the coring-tube being a little greater than the diameter of the fork and the doffer-tube, so that the coring-tube will slide very freely over the said fork and the doffer-tube. The rear end of the 85 coring-tube is rigidly clamped or secured in the lower end of the hanger of the reciprocating frame by means of a bracket, r, which is rigidly affixed to the hanger, and the coring-tube moves or passes through a rigid stop, S, 90 that is curved, as shown, and secured im- 95 movably to the arm or extension of the base-frame, this rigid stop serving to force the apples from the coring-tube during the retrograde movement thereof and force them onto the inclined discharge-plate, from whence they are discharged to one side of the machine.

This being the construction of our improved apple paring and coring machine, the operation 100 thereof is as follows: The machine being in the position shown in Fig. 1, with the swinging arm I elevated immediately in front of the fork, and the coring-tube and the reciprocating frame forced to the extreme rear end of the 105 device, an apple is fitted and secured on the fork by the hand of the operator, the doffer sleeve and collar having been moved to the limit of their motion toward the front end of the shaft F. The operator now turns or rotates the crank of the fly-wheel to simultaneously rotate the shafts E F. The shaft F, the fork, and the fruit thereon are rotated, and as the driving-shaft E is rotated the disk G is likewise actuated. Immediately after the disk 110 G begins to rotate the upper end of the swinging arm I clears the cam rib or shoulder h on the fixed cam-plate H, and the spring then draws the said swinging arm I downwardly, to cause its blades or knives to act upon the 115 fruit and pare the latter. The fruit is thus revolved to continually present a new surface to the action of the cutter-blades, and the blades themselves are shifted or adjusted to occupy different positions relative to the fruit 120 by the rotary disk by which the blades are carried, the spring yielding to the blades whenever they encounter any uneven or irregular surface, and the arm I moving or os- 125 cillating on its trunnions or pivots independ- 130 ently of the rotary movement of the disk G. Simultaneously with the rotary movement of

the disk G the teeth thereof actuate one of the parallel bars *o* to force the reciprocating frame forwardly and also the coring-tube, and this tube first enters the fruit to core the latter 5 when the paring-knives reach the opposite side of the machine from whence they first started, as shown in Fig. 4. The doffer-arm is actuated on by the raised shoulder on the rotary disk to force the doffer-sleeve and tube forward 10 simultaneously with the retrograde movement of the coring-tube and reciprocating frame, that is caused by the teeth on the rotary disk G engaging with the teeth on the opposite rack of the said frame, the swinging arm and the 15 knives carried thereby being elevated above the shaft F and the devices thereon by the upper end of the arm I coming in contact with the depending shoulder on the fixed cam-plate H, so that the said arm and cutting-knives are 20 returned to their first position simultaneously with the retrograde movement of the coring-tube. The fruit on the fork is taken therefrom by the coring-tube during the retrograde movement thereof, and when the fruit comes 25 in contact with the fixed stop S it slides off the tube and drops onto the deflecting-plate of the base. It will thus be seen that the parings from the fruit are dropped onto the inclined rib or flange *b* of the horizontal base during 30 the operation of paring by the knives, while the pared fruit is discharged onto the inclined plate and from thence to the opposite side of the machine, and the cores of the apples are retained in the coring-tube and discharged 35 out of the rear open end thereof.

Our invention is very simple and strong in construction and thoroughly effective and easy of operation.

Various changes in the form and proportion of parts and details of construction can 40 be made without departing from the principle of our invention.

We are aware that it is old in apple paring and coring machines to combine a reciprocating rack carrying a coring-ring, a gear to operate the rack, a swinging knife arm to pare the fruit, and a rotary fork to hold the fruit. We are also aware that it is old to employ a doffer-sleeve to doff the core before the apple 45 is removed from the tines of the fork. We are also aware that it is old to construct the base of such machines with an inclined discharge-plate for the parings of the fruit. These constructions we hereby disclaim.

Having thus fully described our invention, what we claim as new, and desire to secure by Letters Patent, is—

1. In an apple paring and coring machine, the combination of a rotary disk, a reciprocating frame, a hanger rigidly affixed to the frame at one end thereof, a rotary fork arranged beneath the rotary disk and the frame and to one side of the hanger on the latter, a swinging knife-carrying arm supported on the 55 rotary disk to be carried therewith, a coring-tube secured in the lower end of the hanger

and arranged in line with the rotary fork to slide over the same when the frame is moved in one direction, and a stop, through which the coring-tube passes, affixed to the base of the 70 machine to discharge the apple carried by the tube upon the retrograde movement thereof, substantially as described, for the purpose set forth.

2. In an apple paring and coring machine, 75 the combination of a rotating disk, a knife-arm, a reciprocating frame carrying a horizontal coring-tube, a rotary fork arranged in line with the coring-tube and of a smaller diameter than the tube, to thereby permit the latter 80 to slide freely over the fork, a doffer fitted on the fork, a pivoted arm actuated by the disk and impinging against the doffer for moving the latter toward the free end of the fork simultaneously with the retrograde movement 85 of the coring-tube, and the fixed stop arranged at one side of the coring-tube, as and for the purpose described.

3. In an apple paring and coring machine, a frame having a fixed base located beneath 90 the paring and coring devices and provided on its upper surface with an inclined discharge-rib and a discharge-plate arranged in line with the rib and inclined in the reverse direction thereto, whereby the parings and 95 fruit are discharged from the machine in opposite directions, for the purpose set forth.

4. In an apple paring and coring machine, the combination of the reciprocating frame, the hanger affixed to the frame and movable 100 back and forth therewith, a rotary fork arranged beneath the frame and to one side of the hanger, the coring-tube carried by the hanger and arranged in line with the fork to slide over the same, and the independent 105 guide fixed to the base of the machine and working in the lower portion of the hanger to maintain the coring-tube in line with the fork, as and for the purpose described.

5. The combination of a frame provided 110 with inclined discharge flange or rib and the oppositely-inclined discharge-plate arranged to one side of the said rib, the rotary shaft journaled in the frame and carrying a fork, the driving-shaft geared to the rotary shaft, a 115 reciprocating frame, a coring-tube secured on the frame and arranged in line with the fork, and the rotary disk geared to the driving-shaft and reciprocating frame and carrying a pivoted arm having the paring-blade, substantially as described, for the purpose set forth.

6. The combination of a frame having a horizontal base provided with the oppositely-inclined integral rib and plate arranged along 120 side of one another, the rotary shaft journaled in the frame and carrying the fork located above the inclined rib of the base to discharge the parings thereon, the driving-shaft geared to the rotary shaft, the rotary disk geared to 125 the driving-shaft, the reciprocating frame actuated by the rotary disk, the hanger depending

- from the frame, and the coring tube secured in the hanger and arranged in line with the fork and adapted to discharge the fruit upon the inclined plate of the base, the diameter of 5 the said tube being greater than the diameter of the fork, so that the tube can slide over the fork, substantially as described.
7. In a machine for paring and coring fruit, the combination of a horizontal rotary disk 10 having a cam on its upper side, a reciprocating frame actuated thereby and carrying a coring-tube, a rotary fork arranged in line with the coring-tube, a doffer-sleeve fitted loosely on the fork and free to slide back and forth 15 thereon, and a vertically-disposed doffer-arm pivoted at an intermediate point of its length to the frame of the machine and provided at its upper end with an arm which extends over the edge of the rotary disk and is arranged in 20 the path of the cam thereon, the lower end of the doffer-arm being wholly disconnected from the doffer-sleeve and actuating the sleeve through an intermediate device, as and for the purpose set forth.
- 25 8. In a machine for coring and paring fruit, the combination of a rotary disk, a reciprocating frame carrying a coring-tube, a rotary shaft carrying a fork at one end, an endwise-movable doffer-sleeve fitted on the rotary shaft 30 and having the longitudinal slots in which the tines of the fork are fitted to retain the sleeve against rotary movement, a sleeve also fitted loosely on the rotary shaft in rear of the doffer-sleeve, and a pivoted doffer-arm actuated by 35 the rotary disk and impinging at its lower end on the loose sleeve to force the latter against the doffer-sleeve, as and for the purpose described.
9. The combination of a rotary shaft having 40 the fork, a driving-shaft, a rotary disk geared to the shaft and having the raised shoulder or flange, the reciprocating frame having the coring-tube, the slotted doffer-sleeve fitted on the fork-shaft, the flanged collar also fitted on 45 the shaft and bearing against the sleeve thereon, and a pivoted doffer-arm having an angular end, *m*, which impinges on the shoulder of the rotary disk, and an open ring or collar that fits around the fork-shaft and impinges against 50 the flanged collar, substantially as described.
10. In a machine for coring and paring fruit, the combination of a frame provided with a vertical standard, a horizontal cam-plate secured to the upper extremity of the standard 55 and having an inclined shoulder on its lower side, a vertical shaft journaled in the standard and carrying a horizontal rotary disk at its lower end, which is arranged beneath the cam-plate and provided with a transverse opening, 60 a swinging knife-arm pivoted at an intermediate point of its length on the disk and having its upper end passing through the opening in the disk and riding on the inclined shoulder of the cam-plate, a spring connected to the 65 knife-arm and disk, a reciprocating frame geared to the disk and carrying a coring-tube, and a rotary fork, as and for the purpose described.
11. The combination of a frame having a horizontal base provided with the arm or extension and the vertical standard, the fixed cam-plate on the upper end of the standard having the laterally-extended guide-arms, a guide-rod affixed to the extension of the base, 70 a rotary fork, a driving-shaft geared to the shaft, a reciprocating frame arranged beneath the laterally-extended guide-arms, a hanger secured to the frame and having the guide-tube fitting the guide-rod, and a coring-tube secured to 75 the hanger and arranged in line with the rotary fork, substantially as described.
12. In an apple paring and coring machine, the combination of the fork, a reciprocating frame, a movable knife-carrying arm, a hanger 80 affixed to the reciprocating frame, a fixed guide for the hanger on the base of the machine, a coring-tube arranged in line with the fork and secured in the hanger, and a stop on the front end of the fixed guide and arranged at one side 85 of the coring-tube, and against which stop the fruit is adapted to strike during the retrograde movement of the tube and thereby automatically discharge the fruit, substantially 90 as described, for the purpose set forth.
13. In a machine for paring and coring fruit, the combination of a continuously-rotating disk, a frame actuated alternately in one direction and then in the reverse direction by 95 the disk, a rotary fork arranged beneath the disk to one side thereof, a fixed hanger carried by the frame and having a coring-tube arranged in line with the fork, a fixed guide for the hanger, having a stop at its front end and in close proximity to the coring-tube, a swinging 100 knife-arm carried by the disk, and the discharge plates and ribs inclined in reverse directions and arranged beneath the fork and stop, respectively, to discharge the parings and fruit to opposite sides of the machine, as and 105 for the purpose described.
14. In an apple paring and coring machine, the combination, with a rotary fork, of a rotating disk having the gear-teeth *g*² on one side thereof, and a reciprocating frame carrying the 110 coring-tube and having the parallel connected side bars, provided on their inner opposing 115 sides with the gear-teeth, the rotary disk being arranged between the parallel sides of the reciprocating frame and adapted to have its gear-teeth alternately mesh with the teeth on the 120 opposite sides of the frame to move the latter back and forth while the disk rotates in one direction continuously, substantially as described, for the purpose set forth.
15. In an apple paring and coring machine, the combination of a vertical standard having the fixed guide-arms *h*' at its upper end, which 125 guide-arms are arranged in horizontal positions, a horizontal rotary disk journaled in the upper end of the standard, beneath the guide-arms therein, and having the gear-teeth

g^2 , the reciprocating frame having the parallel sides arranged beneath the guides h' and thereby prevented from vertical displacement, the frame having the gear-teeth with which the 5 teeth on the rotary disk mesh to move the frame back and forth, a rotary fork, a coring-tube, and a knife-carrying arm, substantially as described, for the purpose set forth.

In testimony that we claim the foregoing as our own we have hereto affixed our signatures to in presence of two witnesses.
